UNITED STATES PATENT OFFICE.

GEORGE T. PEARSONS, OF NEW YORK, N. Y.

SYRINGE.

1,337,467.

Specification of Letters Patent. Patented Apr. 20, 1920.

Application filed July 29, 1915. Serial No. 42,469.

To all whom it may concern:

Be it known that I, GEORGE T. PEARSONS, a citizen of the United States, residing in the borough of Manhattan, city, county, and State of New York, have invented new and useful Improvements in Syringes, of which the following is a specification.

This invention relates to syringes in which the liquid is discharged from a reservoir by the actuation of a piston therein, and it is the object of the invention to provide a syringe in which the liquid is discharged at each inward and outward movement of the piston.

A further object of the invention is to provide a syringe of this character in which the liquid can be discharged from the reservoir no matter in what position the discharge outlet of the syringe may be.

Another object of the invention is to provide a syringe of this type in which the liquid from the reservoir is discharged by and through a hollow piston at all times connected to the discharge outlet of the reservoir, and so constructed that the liquid in the reservoir normally does not have access to the interior of the piston, but as the latter is reciprocated it is connected to the reservoir and a continuous stream or jet of liquid discharged from the reservoir through the piston.

In the drawings accompanying and forming a part of this specification Figure 1 is a sectional side elevation of a syringe showing an embodiment of my invention.

Figure 1^a is a view similar to Fig. 1 but showing the piston moving upward and discharging liquid.

Fig. 2 is a detailed sectional view of a valve in the piston to connect the piston with the reservoir.

Fig. 3 is a sectional side elevation showing another embodiment of my invention in which the piston chamber and the piston are rotatable in the reservoir.

Fig. 4 is a sectional detailed view of modified means to connect the piston to the discharge outlet.

Fig. 4^a is a cross-sectional view on line A—A of Fig. 4.

Figs. 5, 6, and 7 are sectional side elevations of a syringe showing further embodiments of my invention.

Fig. 6^a is a plan view of Fig. 6.

Similar characters of reference designate

like parts throughout the different views of the drawings.

As a preface to a detailed description of the construction and operation I wish to state that while my improved syringe has been devised for use particularly as a fire extinguisher it may be used for various other purposes.

The embodiment of my invention shown in Figs. 1 and 1^a of the drawings consists of a reservoir 3 for a suitable fire extinguishing liquid, such as carbontetrachlorid, having a discharge outlet or orifice in the formation of a tube 5 supported centrally in one end of the reservoir, such end being provided with a conical projecting nose 5' to constitute a bearing for the discharge tube 5 and to also enhance the appearance of the syringe.

The liquid is discharged from the reservoir by a reciprocable hollow piston or chamber 6 actuated by a rod 7 connected thereto passing through the reservoir and a stuffing box 7' in a removable cover 4, said rod having a hand grip or handle to manipulate the same. The piston is at all times directly connected to and in communication with the discharge outlet 5 by a tube 8 carried by the piston and communicating with the interior thereof slidably engaging in the tube 5. The discharge tube extends somewhat into the reservoir and to permit the piston to move to the bottom of the reservoir it has a tubular portion 9 extending therein for the passage of the discharge tube. The tube 8 extends through this tubular portion 9 and is fixed within the piston, or to one end of the rod 7 which may project into the piston, as shown at 10. To discharge the liquid from the lowermost portion of the piston the inner end of this tube is crooked or bent reversely, as shown at 11, this bend also preventing any exit of liquid which may be in the piston when the syringe is not in use.

The liquid in the reservoir normally does not have access to the interior of the piston, but the piston is so constituted that as it is reciprocated in one direction liquid from one end of the reservoir will enter the piston and be discharged through the tube 8 and outlet 5, and when reciprocated in a reverse direction liquid from the opposite end of the reservoir will enter the piston and be discharged through the tubes 8 and 5. For

this purpose valves, as 12 and 13, are located in opposite ends of the piston. These valves are in the nature of check valves which open inwardly and close outwardly. As shown 5 they consist of heads 14 having stems 15 whereby they are slidably mounted in a bridge 16 extending transverse of a valve seat 17 in ports in the piston ends and normally seated by springs 18. Suitable means 10 such as 14' may be provided to seal the piston in the reservoir.

The reservoir consists of a pair of concentric chambers formed by a pair of tubular members or cylinders 19 and 19' one inside 15 of the other, the inner constituting a piston chamber in which the piston reciprocates, and these chambers are preferably so proportioned that the area of the respective chambers is substantially equal. The upper 20 ends of the cylinders have the common closure 4, and the lower ends are closed by the end 4', or if desired the nose 5' may serve to close the lower ends of said cylinders, the wall 4' being omitted. The inner chamber 25 is connected to the outer chamber at the lower end by ports or openings 22. In the upper end there is provided for each chamber inwardly opening and outwardly closing valves 23 and 24 for a purpose to be 30 hereinafter described. The inner chamber has a supplemental bottom or end 25 with a valve or valves 26 opening into the inner chamber and closing outwardly to connect and disconnect the chambers for the purpose 35 and in the manner hereinafter set forth.

It will be obvious that should there be any injury, such as denting, of the cylinder 19 the inner cylinder will not be injured and interfere with the operation of the piston.

40 To fill the reservoir the end 4 is provided with a pair of filler openings, one for each chamber closed by plugs 21 and 21'.

The operation of the syringe as above described is as follows: The piston is normally 45 in its lowermost position as shown in Fig. 1, and as it is moved upward the valves 12 at the top end of the piston will be unseated and the liquid enters the piston therethrough from the inner chamber and is discharged through tube 8 as shown in Fig. 1^a. Simultaneously with the upward movement of the piston the valves 26 are opened and liquid from the outer chamber drawn into the inner chamber below the piston and the 50 valve 23 is opened and air is drawn into the outer chamber to displace the liquid drawn into the inner chamber. When the piston is moved in a reverse direction or downward the valves 12 in the piston will close and the 55 valves 13 will be unseated and the liquid in the inner chamber below the piston will enter the piston and be discharged through the tube 8. Simultaneously with the downward movement of the piston the valves 23 and 26 will be closed and the valve 24 to

the inner chamber will be opened to permit the entrance of air to displace the liquid which has been discharged therefrom. During the initial operation of the syringe the piston will preferably be given short reciprocating strokes which are gradually increased as the liquid is discharged from the reservoir. After all the liquid has been discharged the plugs 21 and 21' for the filler openings are removed and the respective 70 chambers filled when the syringe is again in condition for use. While I have shown only a pair of valves in each end of the piston it will be obvious that a greater or less number may be provided. Should only two 80 or one valve be provided and the syringe held in a horizontal position with a portion of the liquid discharged the piston may be rotated by the hand grip so that a valve or valves will be in the liquid of the lowermost 85 part of the reservoir. By the provision of the hollow piston and the valves therein the liquid will not have access to the interior of the piston and leakage of the liquid through the discharge outlet is prevented as well as 90 evaporation of the liquid. However, should any liquid remain in the piston due to the bend 11 in the tube such liquid will not leak out through such tube and can only be forced or ejected therethrough as by the 95 pressure of the liquid entering the piston valves. It will be obvious that by this construction there will at all times be liquid at opposite ends of the piston and that such liquid will have access to the piston as it is 100 reciprocated whether the chambers are wholly or only partially filled, or whether the syringe is held in a horizontal position or at an angle to the horizontal.

In Fig. 3 the inner or piston chamber is 105 constructed separate from the cylinder 19 at shown at 19'' and mounted in the reservoir to rotate about the axis of the piston, and the piston is connected to the piston rod 7^a, as at 27, to rotate with the chamber 110 19''. The chamber 19'' is also weighted on one side, as at 28, and provided with valved intakes 29, 29 at opposite ends, whereby as the position of the syringe is changed the intakes will assume a position in the lowermost part of the liquid in the reservoir. The inner or piston chamber has a removable cap 30 which may have a filler opening closed by a plug 31; to fill the two chambers the cover 4 and the plug 31 are removed. And should it be desired to remove the piston and connected mechanism the cover 30 is removed from the chamber 115 19'. The piston valves may consist of flap valves 12^a and 13^a.

To obviate the necessity of the tubular member 9 the tube to connect the piston with the discharge outlet may consist of telescoping sections 8^a and 8^b as shown in Fig. 4. It will be obvious that when the piston 130

moves upward the inner section will draw out from the outer section until it reaches a pre-determined point when the outer section 8^b will be drawn out from the discharge tube 5, and when the piston is moved in a reverse direction the one tube will telescope into the other.

In the construction illustrated in Fig. 5 the inner or piston chamber consists of a tubular member 34 extending from the top to the bottom of the reservoir 3, said tube being connected to the reservoir by ports 35 adjacent the bottom and ports 36. The piston chamber proper is formed by partitions 37 and 38 and located centrally of the reservoir. This chamber is connected at the bottom to the reservoir by a pipe 39 having an inwardly opening and outwardly closing suction valve 40 therein and connected at the upper end to the reservoir by a pipe 41 also extending adjacent the bottom of the reservoir, said latter pipe having a suction valve 42 similar to the valve 40. The outlet from the reservoir is through said chamber by means of a pipe 43 extending to the top of the reservoir and having a flexible hose connected thereto as shown. A hollow piston 6^a having inwardly opening and outwardly closing suction valves in opposite ends, similar to the piston shown in Figs. 1 and 3 operates in said chamber, and the liquid is discharged from the reservoir through the piston by a pipe 44 carried by and communicating with the interior of the piston slidably engaging in the discharge tube 43. The piston is actuated by a rod 45 connected thereto and passing through stuffing boxes in the wall 37 and the top of the reservoir to the exterior thereof and has a hand grip connected thereto. The operation of the syringe in accordance with this construction is substantially the same as that shown in Fig. 1 except that instead of the liquid being ejected from the ends opposite to the operating handle it is ejected from the same end from which the piston is actuated. This type of syringe is particularly adapted for a fire extinguisher of large capacity to stand upon the floor or the like, and to maintain it in a stationary position during the operation the bottom is provided with laterally projecting portions 45' for the engagement of the feet. A locking member 7^a pivotally supported on the top of the reservoir may be provided to engage with a transverse slot in the piston rod to lock the same against movement.

In Figs. 6 and 6^a the piston chamber 19^b extends transversely of the reservoir 3^a and adjacent the top, one end of which chamber is formed with a nose 5^a which extends beyond the side of the reservoir and in which the discharge outlet in the form of a tube 5^b is located similar to the construction shown in Figs. 1 and 3. The opposite end

of the chamber also extends beyond the wall of the reservoir and has an end 46 removably connected thereto and through which the piston rod 7^b passes connected to a piston 6^a, said piston is hollow and has valve controlled inlet ports 12^c and 13^c in opposite ends. The piston 6^a is hollow similar to the construction shown in Figs. 1, 1^a and 3 having valves 12^c, 13^c in opposite ends closing into and opening outward from the piston. The piston also carries a tube 8^c slidably engaging the discharge tube 5^b having a crooked end 11^a within the piston, said tube extending through the tubular portion 9^c of the piston for the engagement of the end of the discharge tube 5^b. The piston chamber has ports 47 and 48 adjacent each end with intake suction valves therein and said intakes are so arranged that they have access to the liquid in the lowermost portion of the reservoir no matter in what position the latter may be held.

To permit of access of the liquid from the lowermost part of the reservoir the ports 47 and 48 at all times and positions of the syringe there is connected thereto a pipe 50 extending to the bottom of the reservoir and connected to the inlets of the piston chamber by a tubular member 51 having branches extending to said inlets, the pipe 50 has ports 52 and 53. Mounted on the pipe 50 to rotate therewith and have a limited sliding movement thereof is a pipe 54 to which is connected pipes 55 and 56 to project laterally therefrom and in the same direction as the pipe 54 to a point adjacent the side of the reservoir. The pipe 56 is adjacent the lower end of pipe 54 and has its intake end adjacent the bottom one side of the reservoir and in the normal position of the syringe registers with the port 53. The pipe 55 is bent so that the intake end is adjacent the top and the side of the reservoir but below the piston chamber 19^b. Access of the liquid from the reservoir in the normal position thereof through this pipe 55 is shut off by the wall of the pipe 50, but should the extinguisher be inverted the pipe 54 with intake pipes 55 and 56 will slide along the pipe 50, the pipe 50 being prevented from moving longitudinally by a collar 57; when the pipe 55 will register with the port 52 the pipe 56 will be out of register with the port 53 and access of liquid therethrough to the pipe 50 shut off by the wall of the latter pipe, this movement being limited by a pin and slot connection 54' between the pipes 50 and 54. It will be obvious that when the syringe is tilted to an angle the pipe 54 will rotate with pipe 50 due to the pin and slot connection 54' on an axis transverse to the axis of the piston chamber, and should the syringe be inverted the intake pipe with its branches will slide along pipe 50 and also rotate about such pipe. The liquid is dis-

charged through the piston and connected tube 6^a, 11^a, the same as in the constructions shown in Figs. 1 and 3 and the construction of the piston and the connection thereof to the discharge outlet is substantially similar except that the piston valves may be in the form of flap valves. The top of the reservoir is removable whereby access may be had to the interior of the syringe, but for ordinary purposes of filling it has an opening closed by plug 59. The cover 58 also has a valved air intake opening 60. This construction of syringe is adapted to be portable and has a conveniently located handle to carry and hold the same.

The syringe shown in Fig. 7 is of the stationary type, and is substantially the same as that shown in Fig. 5 with the exception that compressed air is utilized to eject the liquid from the reservoir. For this purpose an air chamber 66 extends from the top to the bottom of the reservoir in which the discharge outlet of the reservoir is located and is in the form of a tube 67 extending from adjacent the bottom of said chamber and out through the top of the reservoir. The piston chamber is substantially the same as that shown in Fig. 5 having valved intakes 39 and 41. The piston chamber is connected to the air chamber by a pipe 68 having a check valve 69 opening into the air chamber and closing into the piston chamber. The piston 6^c is substantially the same as shown in Fig. 5 having valves 13^a, 12^a opening into and closing outward from the piston and is connected to the air chamber by a pipe 44^a slidably engaging in pipe 68. The operation of this type of syringe is substantially the same as the operation of the construction shown in Fig. 5 with the exception that instead of liquid being directly expelled through the outlet through the piston, it is expelled from the piston into the air chamber compressing air therein and such compressed air ejecting the liquid from the air chamber through the tube 67.

Having thus described my invention, I claim:

1. In a syringe, the combination of a reservoir having a discharge outlet; a tube constituting a continuation of the outlet; a second tube slidably in the first tube; piston mechanism to which the second tube is connected, and a rod to reciprocate the piston mechanism and second tube to draw liquid from the reservoir and discharge the liquid through the reciprocable tube and outlet.

2. In a syringe the combination of a reservoir having a discharge outlet; a cylinder therein; a hollow piston to reciprocate in said cylinder; a rod connected to one end of the piston to extend to the exterior of the reservoir to reciprocate the piston; a tube carried at the opposite end of the piston and communicating with the interior thereof engag-

ing in the reservoir outlet to at all times connect the piston to the outlet of the reservoir; and valves in opposite ends of the piston to connect one end of the piston to the reservoir when moved in one direction and to connect the opposite end of the piston to the reservoir when moved in a reverse direction to discharge the liquid through the piston, piston tube and reservoir outlet during the reciprocation of the piston.

3. In a syringe the combination of a reservoir having a discharge outlet; a hollow piston in said reservoir; a piston rod to reciprocate the piston; a tube carried by the piston and communicating with the interior thereof slidably engaging in the discharge outlet; and check valves in opposite ends of the piston to connect the piston to the reservoir during the reciprocation thereof to discharge the liquid through the piston.

4. In a syringe the combination of a cylinder having a discharge outlet; a hollow piston to fit and reciprocate in said cylinder; a rod connected to the piston and extending to the exterior of the cylinder to reciprocate the piston; a tube carried by and connected to the interior of the piston and slidably engaging in the cylinder outlet to connect the piston to the outlet in all positions thereof; and check valves in opposite ends of the piston to normally cut off communication between the piston and reservoir and operable to alternately connect the piston to the liquid in the cylinder at opposite ends of the piston when the piston is reciprocated to discharge the liquid from the cylinder through the piston, the tube carried thereby and the discharge outlet of the cylinder.

5. In a syringe the combination of a reservoir having a discharge outlet; a hollow piston to reciprocate in the reservoir; a rod connected to the piston extending to the exterior of the reservoir to reciprocate the piston; valves in opposite ends of said piston to connect one end of the piston to the reservoir when moved in one direction and connect the opposite end of the piston to the reservoir when moved in a reverse direction; and a tube carried by and connected to the interior of the piston and slidably engage in the discharge outlet of the reservoir to connect the piston to the reservoir outlet in all positions thereof, the inlet of said tube being so arranged in the piston as to permit exit of the liquid from the piston only during the reciprocation thereof.

6. In a syringe the combination of a reservoir; a cylinder in the reservoir connected at opposite ends to the reservoir and having a discharge outlet at one end; a hollow piston in the cylinder; a rod connected to the piston to extend to the exterior of the cylinder and reservoir opposite to the discharge outlet to reciprocate the piston; a tube reciprocable with the piston at all times connected

to the discharge outlet; and valves in the piston operable during the reciprocation of the piston to alternately connect opposite ends of the cylinder with the discharge outlet 5 through the piston and connected tube.

7. In a syringe the combination of a reservoir having a discharge outlet; a chamber within said reservoir connected to the reservoir at opposite ends of said chamber; a hollow piston to reciprocate in said chamber; a rod connected to the piston to reciprocate the same; means to at all times connect the interior of the piston to the outlet; and valves in opposite ends of said piston; said piston when moved in one direction drawing liquid from one end of the chamber and discharging it through the piston and drawing liquid from the reservoir into the opposite end of the chamber, and when moved in 10 a reverse direction drawing liquid thereinto from said opposite end of the chamber and discharging it through the piston and drawing liquid from the reservoir to the other end of the chamber.
- 25 8. In a syringe the combination of a reservoir having a discharge outlet; a chamber within said reservoir connected at opposite ends to the reservoir; a hollow piston in said chamber; a rod connected to the piston to reciprocate the same; a tube connected to the interior of the piston and slidably engaging in the discharge outlet; and valves in the piston operable when the piston is moved in one direction to connect that end 30 of the chamber with the piston toward which the piston is moving and connect the opposite end of the chamber to the reservoir, and when moved in a reverse direction disconnecting such opposite end of the chamber from the reservoir and connecting it with the piston and shutting off communication between the other end of the chamber with the reservoir and piston, substantially as and for the purpose specified.
- 45 9. In a syringe the combination of a reservoir; a cylinder extending transversely of the reservoir, said cylinder having intakes adjacent opposite ends and having a discharge outlet at one end to the exterior 50 of the reservoir; a piston in said cylinder; a tube carried by the piston at all times connected to the discharge outlet; a rod connected to the end of the piston opposite to the tube and extending to the exterior of the cylinder and reservoir to reciprocate the piston; and a suction inlet connected to the cylinder intakes rotatable about an axis transverse to the axis of the piston and cylinder.
- 55 10. In a syringe the combination of a reservoir; a cylinder extending transversely of the reservoir having an intake adjacent each end and having a discharge outlet at one end to the exterior of the reservoir; a piston in said cylinder; a tube carried by

the piston at all times connected to the discharge outlet; a rod connected to the end of the piston opposite to the tube and extending to the exterior of the cylinder and reservoir to reciprocate the piston; and means connected to the cylinder intakes to at all times connect the cylinder with the liquid in the reservoir in all positions thereof.

70 11. In a syringe, the combination of a reservoir having a discharge outlet; a piston cylinder fixed within the reservoir; suction inlet means to connect the opposite ends of the cylinder to the reservoir and rotatable on an axis transverse to the axis of the cylinder; and piston mechanism to reciprocate in the cylinder arranged to alternately discharge the liquid from the cylinder at opposite sides of the piston mechanism through the outlet during the reciprocation 75 thereof.

80 12. In a syringe, the combination of a reservoir; a cylinder fixed in the reservoir near one end to extend transverse of the reservoir and having an outlet to the exterior 90 of the reservoir; a piston to reciprocate in the cylinder; suction inlets to opposite ends of the cylinder; means to alternately connect the outlet with the cylinder at opposite sides of the piston during the reciprocation 95 of the piston; and intake means to the suction inlets of the cylinder having an inlet near the end of the reservoir opposite the cylinder and an inlet at the end of the reservoir near the cylinder, and adapted to assume a position near that side portion of the reservoir which is lowermost for the purpose specified.

100 13. In a syringe the combination of a reservoir; a cylinder adjacent one end of the reservoir extending transversely of the reservoir having an outlet to the exterior of the reservoir; a reciprocable piston; suction inlets to opposite ends of the cylinder rotatable on an axis transversely of the axis 105 of the cylinder, one of said inlets lying adjacent the end of the reservoir and below the cylinder and the other inlet lying adjacent the opposite end of the reservoir and both being adjacent the side of the reservoir; means to shut off communication between one of said inlets and the cylinder when the other is connected therewith; and valve mechanism to control the entrance of liquid to and its discharge from the cylinder 110 on opposite sides of the piston, substantially as and for the purpose specified.

115 14. In a syringe, the combination of a reservoir; a piston cylinder fixed transversely in said reservoir near one end and having an outlet to the exterior of the reservoir with suction inlets to opposite ends thereof; an intake to said suction inlets movable on an axis transverse of the axis of the piston cylinder arranged to connect the suction inlets 120 125 130

with the liquid near the side of the reservoir and the ends of the reservoir opposite the cylinder and near the cylinder; a piston to reciprocate in the cylinder; and means to alternately discharge the liquid from the piston cylinder at opposite sides of the piston during the reciprocation of the piston.

15. In a syringe the combination of a reservoir; a piston cylinder in said reservoir having an outlet to the exterior of the reservoir and inlets to opposite ends thereof; intakes to said inlets revoluble on an axis centrally of the reservoir and transverse of the axis of the piston cylinder; a reciprocable piston; and means to discharge the liquid from opposite ends of the piston cylinder through the outlet during the reciprocation of the piston.

16. In a syringe the combination of a reservoir; a piston cylinder in said reservoir having an outlet to the exterior of the reservoir and inlets to opposite ends thereof; a pair of intakes to said inlets revoluble on an axis centrally of the reservoir and transverse of the axis of the piston cylinder; valve mechanism to shut off one of said intakes from the cylinder inlets when the other is connected thereto; a piston to reciprocate in the piston cylinder; and means to discharge the liquid from opposite ends of the piston cylinder through the cylinder outlet during the reciprocation of the piston.

17. In a syringe, the combination of a reservoir having a discharge outlet; a tube secured in said outlet constituting a continuation thereof; a piston chamber having suction inlets to opposite ends thereof from the reservoir; a hollow piston in said chamber; a second tube connected to said piston and slidably engaging in the first tube; and a rod to reciprocate said piston; said piston being arranged and adapted to alternately draw liquid to and discharge it from the piston chamber at opposite sides of the piston through the slidable tube and outlet.

18. In a syringe, the combination of a

reservoir having an outlet; a piston cylinder fixed within said reservoir; an intake to the piston cylinder rotatable on an axis transverse to the axis of said cylinder and arranged to draw the liquid from the reservoir near the side and ends of the reservoir, and piston mechanism to draw liquid from the reservoir into the piston cylinder through the intake and discharge it through the reservoir outlet.

19. In a syringe, the combination of a reservoir having an outlet; a piston cylinder in said reservoir having suction inlets to opposite ends thereof; means rotatable on an axis transverse to the axis of the piston cylinder to connect the suction inlets with the liquid in the reservoir adjacent the end of the reservoir and the wall of the reservoir opposite to the piston cylinder and adjacent the piston cylinder; a reciprocable piston; and means to discharge the liquid from opposite ends of the piston cylinder during the reciprocation of the piston.

20. In a fire extinguisher, the combination with a reservoir to contain liquid, of a piston cylinder having closures secured to opposite ends and connected immovably at opposite ends in the reservoir and having inlet ports to opposite ends thereof; a piston to reciprocate in said cylinder; a fixed tubular member in the reservoir in communication with the inlet ports of the piston cylinder; intake means connected to said tubular member comprising tubes having inlets from opposite ends of the reservoir and adapted to assume variable positions near the side of the reservoir; valve mechanism operable to shut off the liquid from the reservoir to the piston cylinder through an intake tube when the piston cylinder is connected to the reservoir through the other intake tube; and valve mechanism operable through the reciprocation of the piston to control the entrance of liquid to and its discharge from the piston cylinder at opposite sides of the piston.

GEO. T. PEARSONS.
